DESIGN FOR A COMBINED EASEL AND FRAME

Joseph Halpern, New York, N. Y.

Application November 20, 1943, Serial No. 111,751

Term of patent 7 years

To all whom it may concern:

Be it known that I, Joseph Halpern, a citizen of the United States of America, residing in New York city, county of Bronx and State of New York, have invented a new, original, and ornamental Design for a Combined Easel and Frame, of which the following is a specification, reference being had to the accompanying drawing, forming part thereof, wherein,

I claim:

The ornamental design for a combined easel and frame, substantially as shown.

JOSEPH HALPERN.
